UNITED STATES PATENT OFFICE

RUPERT E. RUNDELL, OF ROCKVILLE CENTER, AND GUSTAF E. HAGQUIST, OF BROOKLYN, NEW YORK, ASSIGNORS TO INTERNATIONAL CIGAR MACHINERY COMPANY, A CORPORATION OF NEW JERSEY

LEAF STEMMING MACHINE

Application filed February 18, 1931. Serial No. 516,789.

This invention relates to a leaf stemming machine, particularly designed to rapidly remove the stems of tobacco leaves to prepare their webs for use as cigar fillers.

5 Heretofore, leaves for this purpose have been stemmed by hand, for the reason that no machine suitable for the purpose was available.

There are machines in use in the cigar 10 making industry that cut out the stems and book expensive cigar wrapper tobacco, but in their use the leaves must be spread out and kept spread out by hand during the stemming operation. Their output is restricted 15 by this necessity, too restricted to be economical in stemming the much cheaper filler tobacco. They do not tear the stems and webs apart as in manual stemming.

There are also machines in use in the cigarette making industry that scrape or mill 20 the webs of leaves off their stems, and they operate much faster than the cigar wrapper stemming and booking machines, but in their use the webs of the leaves unavoidably become crumpled during the stemming operation. They do not tear the stems and webs apart as in manual stemming. The crumpling of the leaf webs is not detrimental in 25 cigarette manufacture, for the reason that they are cut into shreds after stemming. But cigar fillers are not shredded, and to first stem and then de-crumple leaf webs stemmed in such machines would cost as much if not more 30 than hand stemming.

35 In manually stemming tobacco, the operator seizes the stem at a point near its tip with one hand, breaks it off at that point, seizes the web with the other hand, and then separates the hands in divergent directions to rapidly tear the stem and web apart 40 toward the butt of the leaf, as a person might tear a piece of paper into two pieces. This tearing action is unlike the cutting, scraping or milling action of any machine heretofore known, and it must be effected in a direction 45 toward the butt of the leaf, for the reason that in tearing the stems and webs apart in this way the branch ribs or veins are readily torn from the midrib or stem with the web, while in tearing the web from the stem

in the opposite direction the tearing web will follow the angularly disposed branch ribs without breaking them off the stem, and thus effectually block the stemming operation.

55 A major object of the invention is the production of a machine which is capable of automatically spreading out leaves from which their stems are to be removed, and then automatically tearing their stems and webs apart 60 toward their butts, in simulation of manual stemming, but much more rapidly, to avoid or overcome the mechanical and economic difficulties heretofore encountered in preparing tobacco for cigar fillers. Another major 65 object of the invention is the production of such a machine in which the leaves to be stemmed are passed through a suction chamber having air exhausting connections, to 70 cause outgoing air to spread them out. Still another major object of the invention is the production of such a machine in which outspread leaves are passed through stemming devices including stem holding means and 75 web holding means traveling in divergent directions, to effect the separation of the stems and webs. With these major objects, and certain minor objects not specifically mentioned, in view, the invention consists in certain constructions and combinations which 80 will be hereinafter fully described and then specifically set forth in the claims hereunto appended.

85 In the accompanying drawings, which form a part of this specification and in which like characters of reference indicate the same or like parts, Fig. 1 is a front elevation partly broken away of a machine embodying the invention; Fig. 2 is a side elevation partly in section of the machine shown in Fig. 1; Fig. 3 is a detail sectional plan view on the line 3—3 of Fig. 1; Fig. 4 is a detail view in front elevation, partly in section, of the suction web-holding roll shown in Fig. 1; Fig. 5 is a detail sectional view on the line 5—5 of Fig. 4; Fig. 6 is a detail view in front elevation of the stem holding means shown in Fig. 1; Fig. 7 is a sectional view on line 7—7 of Fig. 6; Figs. 8 and 9 are detail views of the stem holding means illus- 95 100

trated in Figs. 1 and 6 showing the operation thereof; Fig. 10 is a detail view in front elevation illustrating the operation of the knives shown in Fig. 1; Fig. 11 is a sectional side elevation of a modified web holding and stem holding mechanism for carrying out the invention; Figs. 12 and 13 are detail views in front elevation illustrating the operation of the devices shown in Fig. 11; Figs. 14, 15, 16 and 17 are detail views showing the operation of the mechanisms illustrated in Fig. 11.

In carrying the invention into effect there is provided mechanism for spreading out leaves from which their stems are to be removed, of stemming devices receiving outspread leaves from said mechanism and tearing their stems and webs apart toward their butts to thereby remove the stems in a manner similar to hand stemming. In the best constructions said mechanism includes a suction chamber having air exhausting connections and means for passing leaves through said chamber to cause outgoing air to spread them out. The best constructions also include means for transporting the the outspread leaves from the suction chamber to the stemming devices. Preferably the stemming devices include stem holding means, web holding means, and means for causing said stem holding means and said web holding means to travel in divergent directions. Preferably said devices include gang grippers for holding the stems of the leaves despite variations in the lateral position at which the stems are received by the devices. The best constructions further include a leaf support delivering leaves to said mechanism.

The various means referred to may be varied widely in construction within the scope of the claims, for the particular device selected to illustrate the invention is but one of many possible concrete embodiments of the same. The invention therefore is not to be restricted to the precise details shown and described.

Referring to Figs. 1, 2 and 3, the leaves L to be stemmed are hung on spring clips 11 on a leaf transport conveyer 12 running over sprockets 13. Each transport clip when arriving at the stemming station, engages with a stationary inclined cam surface 14 which opens the clip after the stem S has been gripped by a leaf support having a clamp 15 fastened to an arm 16 carried by a vertical rod 17 slidable in bearings 18.

An arm 19 guided by the stationary vertical rod 20 moves the rod 17 up and down by means of a cam operated rod 21. When in its lowermost position, the clamp 15 engages with a stationary vertical cam 22 held by an arm 23 extending from bearing 18, thereby opening the clamp and releasing the leaf as it passes into the leaf spreading and stemming mechanism.

As the leaf is lowered on rod 17, it is guided

by the flaring lips 24 into the mouth of a narrow chamber 25, constructed in a direction perpendicular to the plane in which the leaf is supported at either side of which are air exhausting connecting pipes 26 to a suction fan or similar air exhausting means, the two halves of chamber 25 having between them grooved strips 27 resiliently supported by parts 27a, 27b, 27c and spaced from the edges of the chamber to admit air along the central portion of the leaf. The shallow or constricted shape of the chamber perpendicular to the plane along which the leaf is passed gives the air passing from the center to the outside of the chamber increased force and velocity along the web and toward the edge of the leaf, thus forcibly uncurling and spreading out the web and edges of the leaf and at the same time subjecting the moving and waving web to a powerful cleaning action. Belts 28 running over rollers 29 and 30 carry the leaf L through chamber 25, the inner runs of belts 28 running in the grooves of the strips 27. As the leaves pass through the chamber 25, they are spread out flat by the suction which acts in the direction of the arrows. Emanating from between the rollers 30 the leaves are guided by belts 31 running over rollers 30 and 32. As shown in Fig. 1 the outlet edges of the chamber are cut to a broad inverted V contour in order to give the air sucked in at this position a lateral leaf spreading component instead of too much of a vertical movement which might permit wrinkling of the leaf transversely.

The suction chamber and means for passing the leaves through it also thoroughly cleans the leaves. As is well known, tobacco leaves have grit, field dirt, clay and the like stuck to the web, which in practice is very difficult to thoroughly remove. In the present device, due to the combined spreading, waving and longitudinal movements of the leaf all of which loosens the dirt and to the strong suction action to which the loosened dirt is exposed, thorough cleaning results. Accordingly, applicant obtains the valuable result of better cleaning than heretofore with no additional mechanism and no additional time consumed, by the same means that spread the leaf and present it for stemming.

The rear set of the rollers 29 and 30 is held in stationary bearings 33, while the front set is supported in slidable bearings 34 which are held in tension against the rear rollers by springs 35. Similarly, while the rear roller 32 is journaled in a stationary bearing 36, the front roller 32 is hung from shaft 37 of the front roller 30 by arms 38 which are tensioned against the rear roller by springs 39 pulling the shaft 40 towards the supporting frame of the machine. The rear roller 30 is driven from the main shaft 41 of the machine by the chain 42, and through gears 43 drives the front roller 30, thus imparting

motion to belts 28 and 31, the foregoing serving to pass the leaf through the suction chamber without interfering with the spreading of the leaf. The outspread leaves passed 5 through the chamber are received on the surface of a perforated, cylindrical sleeve positioned to intercept the leaves, Figs. 4 and 5, which rotate about a stationary hollow apertured suction box 45 having at one end a pipe 10 46 connected with the suction pipe 26. The sleeve 44 is mounted on a shaft 47 carried by the drum 45 and has a gear 48 at one end of its circumference. Toward the rear, the drum 45 has an opening 49 through which 15 the suction communicates with the perforations of cylindrical sleeve 44. The tip of the leaf, having been taken along by the motion of sleeve 44, is by the suction held fast to this sleeve 44 as soon as the latter comes 20 opposite the opening 49 and is thus carried to the point where the leaf is securely gripped between the sleeve and a loop of a conveyer belt 50 running over rollers 51, 52 and 53, the roller 51 being driven by chain 54 from main 25 shaft 41. The conveyor 50 delivers the stemmed leaves L from the machine in a perfectly flat condition, ready to be stacked for subsequent treatment. Thus the suction on sleeve 44 holds the web outspread and 30 flat and out of the range of the grippers while the stem is being gripped and the belt 50 and sleeve together hold the tip against being pulled back by the pull on the stem.

On main shaft 41 is mounted stem holding means which includes a cylinder 55, Figs. 6 and 7, having a series of inclined axially spaced circumferential flanges 56 and carrying axial plungers 57. Each plunger has a row of inclined pins 58 corresponding in 40 number with the number of grooves 56 and extending to the surface of the drum 55 through radial slots 59 cut into flanges 55.

These pins 58 form with the slotted flanges a transversely extending gang of grippers 45 which grip the stem despite feeding of the leaf with the tip a substantial distance to either side of central position. This constitutes an important feature of applicants' device, since it makes possible mechanical 50 tip first feeding of the leaf without the careful manual grinding of the stem required by most types of stemmers such as those of the stemming and booking machines previously mentioned. This also provides for efficient 55 gripping of laterally offset crooked and broken stem portions, which prior devices have commonly failed to take out. The foregoing applies also to the modified form illustrated in Figs. 11 to 17 inclusive. The 60 plungers 59 have rollers 60 by which they bear against a stationary cam 61 attached to bearing 62 of shaft 41. Springs 63 bearing against a disk 64 mounted on shaft 41 press the rollers 60 against the surface of 65 cam 61. A gear 65 mounted on shaft 41

meshes with gear 48 of cylinder 44. The inclination of the flanges is in the opposite direction to that of the pins 58, so that the pins make nearly equilateral acute angles with the sides of the flanges towards which they are pointed, thus producing a double wedge effect on a stem held between them. 70

As the leaf L on sleeve 44 comes nearest contact with cylinder 55 in the horizontal plane passing through the centers of shafts 75 41 and 47, the plunger 57' in that plane at the time, drops into the track of cam 61, thereby causing its grippers 58 to move in the slots 59' across the opposed flange 56. This action is repeated by every plunger 57 80 as it arrives in the horizontal plane, and as soon as the stem S of leaf L becomes thick enough to penetrate between the flanges and pins 56, the pin 58' presses the stem against the inclined side of the flange and thereby 85 grips it as shown in Fig. 8. Since this action is taking place continually as the leaf travels around cylinder 44, the stem S is gripped anew as every plunger passes through the contact plane so that even a 90 broken stem such as that shown in Fig. 8 is perfectly removed from the leaf, the cam 61 being so arranged that a number of gripper pins 58 in tandem are in engagement with the stem at the same time. Thus, in Fig. 8, 95 the end S' of the stem is held fast by one of the grippers 58'' in the row just opposite the contact plane, while the next section S is gripped by one of the grippers 58' in the contact row. Since the gripper cylinder 55 100 is rotated in the opposite direction from sleeve 44 the stem and the web are carried along divergent paths tearing out the stem from tip to butt in a manner simulating hand stemming. 105

The distance between the suction sleeve 44 and the gripper cylinder 55, at the outside diameter of the flanges 56, is adjusted to accommodate the thickness of the leaf portion and so much of the small end of the stem as 110 it is desired to leave in the leaf. Thus a portion of the stem larger than the distance between sleeve and flanges will project into the grip of the gripping means regardless of whether the leaf lies front side up or down 115 on cylinder 44 as shown in Fig. 9. In Fig. 9, which gives a sectional top view of the gripping device showing the double wedge effect produced on the stem by the action of the inclined pin and the inclined groove, the leaf 120 L lies with its back on sleeve 45 and its stem S is pressed in between the flanges 56 so that pin 58' grips the stem through the pressed in portion of the leaf instead of by direct engagement as when the front of the leaf is towards the sleeve 44 and its back with the stem protruding is towards the cylinder 55. Both the cylinder 44 and the drum 55 have rotating brushes, 66 and 67, in engagement with their surfaces for the pur- 125 130

pose of stripping from them the stemmed leaves L and the stems S, respectively, and of cleaning them of dust and tobacco scraps.

The stem S, when pulled away from the leaf L on cylinder 44 by the rotation of drum 55, pulls it along or bellies it to a greater or less degree. In case the leaf fails to tear out, the abnormally bellied leaf engages with a horizontally reciprocating knife set at a proper angle or preferably with the diverging edges of two coating rotary knives 68 and 69 driven in opposite directions by belts 70 and 71 from a double pulley 72. The knives 68 and 69, entering between the gripped stem S and the tightly stretched leaf L, as shown in Fig. 10, rip the leaf close to the stem and thus restart the normal tearing action. Preferably the knives are so set that they do not act till abnormal resistance to tearing is encountered. The stems S ejected from the drum 55 by the brushes 67 drop into a chute 73 which deposits the same into a receptacle provided for the purpose.

Since the portions of the stem near the tip are unobjectionable and add to the weight of filler tobacco and the size of the stem portion to be left in varies with tobaccos and cigar manufacturers' requirements, it is desirable that the operator be able to select the thickness at which the stemming means starts tearing out the stem. For this purpose as shown in Fig. 2 the sleeve 44 and gripper cylinder 55 are made relatively adjustable toward or away from each other by mounting bearing blocks 85 journalling the shaft 47 of the sleeve 44 and supporting suction box therein for horizontal movement in a slide-way in the frame 84, its position being accurately adjustable by means of a cap screw 86 threaded in the frame and rotatably secured by a groove and pin 87 to the block.

In order to adjustably position the roller 52 to cause the belt 50 to grip various sizes and types of leaves at variable distances from the tearing point and in order to widen the apex between the belt and sleeve 44 when desirable, this roller is adjustably supported. As shown in Fig. 2 this is accomplished by securing to a bracket 89, on the frame 88 by

means of a screw passing through a slot in a supporting piece 90. This supporting piece carries at its outer end a pivoted lever 91 supporting at one end the roller 52, and engaging at its opposite end a set screw 92 by which the roller 52 can be swung out from the sleeve 44. By means of the slotted connection of piece 90 to the bracket the roll may be moved further in to the bight of the sleeve 44 and cylinder 55.

In Figs. 11 to 17, a modification of the stem stripping unit is shown, use being made of a carded drum for gripping the stems. The leaf L delivered by the belts 31 onto the suction cylinder 44 is tightly pressed against the said cylinder by two endless belts

74 running over rollers 75, these belts being so placed on cylinder 44 that the stem S of the leaf comes in the space between them. Into the latter space is placed a carded drum 76 mounted on a shaft 77 supported in bearing 78, the drum 76 having stem impaling pins 79 extending to within a leaf thickness or small stem thickness toward the surface of cylinder 44 and arranged in staggered circumferential rows, the pins in each row being but little more than one stem thickness apart. The drum 76 is rotated in the same direction as cylinder 44 so that their adjoining surfaces move in opposite directions as indicated by arrows. Coacting with the carded drum 76 is a second drum 80 mounted on shaft 81 in bearing 82, the shaft 81 being eccentric with respect to shaft 77. In the circumference of drum 80 are mounted as many horizontally projecting pins 83 as there are horizontal rows of pins 79 on drum 76, the pins 83 projecting across all of the pins 79 in each of the horizontal rows. The eccentricity of the shafts 77 and 81 is such that the pins 83 on the side towards cylinder 44 lie at the foot of pins 79 and on the side away from cylinder 44 they lie at the top of the carding pins. When a leaf enters the space between the cylinder 44 and carded drum 76, Fig. 15, the pins 79 engage the stem S as soon as the arriving stem becomes thick enough to protrude a sufficient distance from the leaf, the stem becoming impaled and caught on the nearest pins. As more and more of the pins 79 take hold of stem S, Fig. 16, the latter is carried partly around drum 76 which is rotated with a slightly greater surface speed than cylinder 44 so as to exert a pulling action on the stem which is thereby stripped from the leaf L while the latter is held against cylinder 44 by the belts 74. As the drum 76 turns around, the horizontal pins 83, due to the eccentric mounting of drum 80, rise higher and higher between the carding pins 79 until, near the far side of drum 76, Fig. 17, they reach the tops of the carding pins and thus push the stem from the drum.

What is claimed is:

1. The combination with mechanism for spreading out leaves from which their stems are to be removed, of stemming devices receiving outspread leaves from said mechanism and tearing their stems and webs apart toward their butts.

2. The combination with mechanism for spreading out leaves from which their stems are to be removed, of stemming devices receiving outspread leaves from said mechanism and tearing their stems and webs apart toward their butts, and a leaf support delivering leaves to said mechanism.

3. The combination with mechanism for spreading out leaves from which their stems are to be removed, of stemming devices re-

- ceiving outspread leaves from said mechanism and tearing their stems and webs apart toward their butts, a leaf support delivering leaves to said mechanism, and a leaf trans-
5 port supplying leaves to said support. 70
4. The combination with mechanism for spreading out leaves from which their stems are to be removed, of stemming devices receiving outspread leaves from said mechanism and tearing their stems and webs apart toward their butts, said mechanism including a suction chamber having air exhausting connections, and means for passing leaves through said chamber to cause outgoing air
10 to spread them out. 75
5. The combination with mechanism for spreading out leaves from which their stems are to be removed, of stemming devices receiving outspread leaves from said mechanism and tearing their stems and webs apart toward their butts, said mechanism including a suction chamber having air exhausting connections, and coacting belts for passing leaves through said chamber to cause outgoing air to spread them out. 80
6. The combination with mechanism for spreading out leaves from which their stems are to be removed, of stemming devices receiving outspread leaves from said mechanism and tearing their stems and webs apart toward their butts, said mechanism including a suction chamber having air exhausting connections, means for passing leaves through said chamber to cause outgoing air to spread them out, and means for transporting the outspread leaves from said chamber to said devices. 85
7. The combination with mechanism for spreading out leaves from which their stems are to be removed, of stemming devices receiving outspread leaves from said mechanism and tearing their stems and webs apart toward their butts, said mechanism including a suction chamber having spaced walls
40 terminating at their outer edges in oppositely disposed air exhausting connections, shafts outside said walls, and coacting belts operated by said shafts and having operating runs between said walls for passing leaves
45 through said chamber to cause outgoing air to spread them out. 90
8. The combination with mechanism for spreading out leaves from which their stems are to be removed, of stemming devices receiving outspread leaves from said mechanism and tearing their stems and webs apart toward their butts, said devices including stem holding means, web holding means, and means for causing said stem holding means
55 and said web holding means to travel in divergent directions. 95
9. The combination with mechanism for spreading out leaves from which their stems are to be removed, of stemming devices receiving outspread leaves from said mecha-
60 nism and tearing their stems and webs apart toward their butts, said devices including
65
- nism and tearing their stems and webs apart toward their butts, said devices including gang grippers for holding the stems of leaves, web holding means, and means for causing said grippers and said web holding means to travel in divergent directions. 100
10. The combination with mechanism for spreading out leaves from which their stems are to be removed, of stemming devices receiving outspread leaves from said mechanism and tearing their stems and webs apart toward their butts, said devices including stem holding means, suction web holding means, and means for causing said stem holding means and said suction web holding means to travel in divergent directions. 105
11. The combination with mechanism for spreading out leaves from which their stems are to be removed, of stemming devices receiving outspread leaves from said mechanism and tearing their stems and webs apart toward their butts, said devices including an apertured cylindrical suction box, a perforated sleeve rotating on and co-acting with said box to hold the webs of leaves, and stem holding means rotating in the opposite direction. 110
12. The combination with mechanism for spreading out leaves from which their stems are to be removed, of stemming devices receiving outspread leaves from said mechanism and tearing their stems and webs apart toward their butts, said devices including an apertured cylindrical suction box, a perforated sleeve rotating on and co-acting with said box to hold the webs of leaves, a belt pressing against said sleeve, and stem holding means rotating in the opposite direction. 115
13. The combination with mechanism for spreading out leaves from which their stems are to be removed, of stemming devices receiving outspread leaves from said mechanism and tearing their stems and webs apart toward their butts, said devices including stem holding means comprising a rotating cylinder provided with axial slots, and spring-pressed and cam-controlled gang grippers working in said slots. 120
14. The combination with mechanism for spreading out leaves from which their stems are to be removed, of stemming devices receiving outspread leaves from said mechanism and tearing their stems and webs apart toward their butts, and a leaf support delivering leaves to said mechanism, said support including means for supporting a leaf by its butt. 125
15. The combination with mechanism for spreading out leaves from which their stems are to be removed, of stemming devices receiving outspread leaves from said mechanism and tearing their stems and webs apart toward their butts, and a leaf support delivering leaves to said mechanism, said support including a gripper for supporting a
130

leaf by its butt, and means for lowering said gripper to effect leaf delivery to said mechanism.

16. The combination with mechanism for spreading out leaves from which their stems are to be removed, of stemming devices receiving outspread leaves from said mechanism and tearing their stems and webs apart toward their butts, and a leaf support delivering leaves to said mechanism, said support including a gripper for supporting a leaf by its butt, an arm carrying said gripper, a rod carrying said arm, means for lowering said rod to effect leaf delivery to said mechanism, and means for releasing said gripper when in its lowermost position.

17. The combination with mechanism for spreading out leaves from which their stems are to be removed, of stemming devices receiving outspread leaves from said mechanism and tearing their stems and webs apart toward their butts, a leaf support delivering leaves to said mechanism, and a leaf transport supplying leaves to said support, said transport including a traveling chain provided with a plurality of spring clips for carrying leaves by their butts.

18. The combination with mechanism for spreading out leaves from which their stems are to be removed, of stemming devices receiving outspread leaves from said mechanism and tearing their stems and webs apart toward their butts, a leaf support delivering leaves to said mechanism, and a leaf support supplying leaves to said support, said transport including a traveling chain provided with a plurality of spring clips for carrying leaves by their butts, and a stationary cam in the path of said clips for releasing them as leaves are delivered.

19. The combination with mechanism for spreading out leaves from which their stems are to be removed including a suction chamber having air exhausting connections, of means for passing leaves through said chamber to cause outgoing air to spread them out, and stemming devices receiving outspread leaves from said mechanism and separating their stems and webs.

20. The combination with mechanism for spreading out leaves from which their stems are to be removed including a suction chamber having air exhausting connections, of means for passing leaves through said chamber to cause outgoing air to spread them out, stemming devices receiving outspread leaves from said mechanism and separating their stems and webs, and a leaf support delivering leaves to said mechanism.

21. The combination with mechanism for spreading out leaves from which their stems are to be removed including a suction chamber having air exhausting connections, of means for passing leaves through said chamber to cause outgoing air to spread them out,

stemming devices receiving outspread leaves from said mechanism and separating their stems and webs, a leaf support delivering leaves to said mechanism, and a leaf transport supplying leaves to said support.

22. The combination with mechanism for spreading out leaves from which their stems are to be removed including a suction chamber having air exhausting connections, of means for passing leaves through said chamber to cause outgoing air to spread them out, and stemming devices receiving outspread leaves from said mechanism and separating their stems and webs, said passing means including coacting belts running through said chamber.

23. The combination with mechanism for spreading out leaves from which their stems are to be removed including a suction chamber having air exhausting connections, of means for passing leaves through said chamber to cause outgoing air to spread them out, and stemming devices receiving outspread leaves from said mechanism and separating their stems and webs, said mechanism including means for transporting outspread leaves from said chamber to said devices.

24. The combination with mechanism for spreading out leaves from which their stems are to be removed including a suction chamber having air exhausting connections, of means for passing leaves through said chamber to cause outgoing air to spread them out, and stemming devices receiving outspread leaves from said mechanism and separating their stems and webs, said chamber including spaced walls terminating at their outer edges in oppositely disposed air exhausting connections, and said passing means including shafts outside of said walls and coacting belts operated by said shafts and having operating runs between said walls.

25. The combination with mechanism for spreading out leaves from which their stems are to be removed including a suction chamber having air exhausting connections, of means for passing leaves through said chamber to cause outgoing air to spread them out, and stemming devices receiving outspread leaves from said mechanism and separating their stems and webs, said chamber including spaced walls terminating at their outer edges in oppositely disposed air exhausting connections, and said passing means including shafts outside of said walls and beyond the same, and coacting belts operated by said shafts for passing leaves through said chamber and thence to said devices.

26. The combination with mechanism for spreading out leaves from which their stems are to be removed including a suction chamber having air exhausting connections, of means for passing leaves through said chamber to cause outgoing air to spread them out, stemming devices receiving outspread leaves

from said mechanism and separating their stems and webs, and a leaf support delivering leaves to said mechanism, said support including means for supporting a leaf by its 5 butt.

27. The combination with mechanism for spreading out leaves from which their stems are to be removed including a suction chamber having air exhausting connections, of 10 means for passing leaves through said chamber to cause outgoing air to spread them out, stemming devices receiving outspread leaves from said mechanism and separating their stems and webs, a leaf support delivering 15 leaves to said mechanism, said support including a gripper for supporting a leaf by its butt, and means for lowering said gripper to effect leaf delivery to said mechanism.

28. The combination with mechanism for 20 spreading out leaves from which their stems are to be removed including a suction chamber having air exhausting connections, of means for passing leaves through said chamber to cause outgoing air to spread them out, 25 stemming devices receiving outspread leaves from said mechanism and separating their stems and webs, a leaf support delivering leaves to said mechanism, said support including a gripper for supporting a leaf by 30 its butt, an arm carrying said gripper, a rod carrying said arm, means for lowering said rod to effect leaf delivery to said mechanism, and means for releasing said gripper when 35 in its lowermost position.

29. The combination with mechanism for 40 spreading out leaves from which their stems are to be removed including a suction chamber having air exhausting connections, of means for passing leaves through said chamber to cause outgoing air to spread them out, 45 stemming devices receiving outspread leaves from said mechanism and separating their stems and webs, a leaf support delivering leaves to said mechanism, and a leaf transport supplying leaves to said support, said transport including a traveling chain provided with a plurality of spring clips for carrying leaves by their butts.

30. The combination with mechanism for 50 spreading out leaves from which their stems are to be removed including a suction chamber having air exhausting connections, of means for passing leaves through said chamber to cause outgoing air to spread them out, 55 stemming devices receiving outspread leaves from said mechanism and separating their stems and webs, a leaf support delivering leaves to said mechanism, a leaf transport supplying leaves to said support, said trans- 60 port including a traveling chain provided with a plurality of spring clips for carrying leaves by their butts, and a stationary cam in the path of said clips for releasing them as leaves are delivered.

31. The combination with a leaf support,

of a suction chamber having air exhausting connections, means for producing a relative movement of said support and said chamber to cause leaves to enter said chamber and be spread out by outgoing air, and stemming devices receiving outspread leaves from said chamber and tearing their stems and webs apart toward their butts in simulation of manual stemming.

32. The combination with a leaf support, 75 of a suction chamber having air exhausting connections, and means for producing a relative movement of said support and said chamber to cause leaves to enter said chamber and be spread out by outgoing air.

33. The combination with a leaf support, 80 of a suction chamber having air exhausting connections, and means for moving said support toward said chamber to cause leaves to enter said chamber and be spread out by outgoing air.

34. The combination with a leaf transport, 85 of a leaf support receiving leaves from said transport, a suction chamber having air exhausting connections, and means for producing a relative movement of said support and said chamber to cause leaves to enter said chamber and be spread out by outgoing air.

35. The combination with a leaf transport 90 having a plurality of spring clips for holding leaves by their butts, of a leaf support receiving leaves from said clips, means for releasing said clips as leaves are delivered to said support, and means for lowering said support to carry a leaf away from said transport.

36. The combination with a leaf transport 95 having a plurality of spring clips for holding leaves by their butts, of a leaf support having a gripper for supporting a leaf by its butt and receiving leaves from said clips, means for lowering said gripper to carry a leaf away from said transport, and a stationary cam for releasing said gripper when in 100 its lowermost position.

37. The combination with a leaf transport including a traveling chain having a plurality 105 of spring clips for holding leaves by their butts, of a leaf support having a gripper for supporting a leaf by its butt and receiving leaves from said clips, a stationary cam for releasing said clips as leaves are delivered to said support, and means for lowering said support to carry a leaf away from said trans- 110 port.

38. The combination with a leaf support 115 having a gripper for supporting a leaf by its butt, an arm carrying said gripper, a rod carrying said arm, and means for lowering 120 said rod to lower a leaf in said gripper with its tip lowermost.

39. The combination with a leaf support 125 having a gripper for supporting a leaf by its butt, of reciprocating means for lowering 130

said gripper to lower a leaf carried thereby with its tip lowermost.

40. The combination with a leaf support, of a suction chamber below said support and having air exhausting connections, and means for lowering said support to cause a leaf carried thereby to enter said chamber tip first and be spread out by outgoing air.

41. The combination with a leaf support 10 having a gripper for supporting a leaf by its butt, of a suction chamber below said support and having air exhausting connections, means for lowering said support to cause a leaf carried thereby to enter said chamber tip first 15 and be spread out by outgoing air, and means for releasing said gripper when the leaf has entered said chamber.

42. The combination with a leaf transport having a plurality of spring clips for holding 20 leaves by their butts, of a leaf support having a gripper for supporting a leaf by its butt and receiving leaves from said transport, a stationary cam in the path of said clips for releasing them as leaves are delivered to said support, a suction chamber below said support and having air exhausting connections, means for lowering said support to cause a leaf carried thereby to enter said chamber tip first and be spread out by outgoing air, and a stationary cam for releasing 30 said gripper when the leaf has entered said chamber.

43. The combination with a suction chamber having air exhausting connections, of 35 means for passing a leaf therethrough to cause outgoing air to spread it out.

44. The combination with a suction chamber having air exhausting connections, of a pair of coacting belts for passing a leaf therethrough to cause outgoing air to spread it out.

45. The combination with a suction chamber having air exhausting connections, of means for passing a leaf therethrough to cause outgoing air to spread it out, and additional means for transporting the outspread leaf away from said chamber.

46. The combination with a suction chamber having air exhausting connections, of means for passing a leaf therethrough to cause outgoing air to spread it out, and coacting belts for transporting the outspread leaf away from said chamber.

47. The combination with stemming devices acting on a leaf to tear its stem and web 55 apart toward its butt, of rotating knives associated therewith to aid the tearing action when abnormal resistance occurs.

48. A leaf support for stemming machines, comprising a gripper for supporting a leaf 60 by its butt, an arm carrying said gripper, a rod carrying said arm, means for reciprocating said rod, and means for releasing said gripper at one end of its movement.

49. A leaf support for stemming machines, 65 comprising a gripper for supporting a leaf

by its butt, an arm carrying said gripper, a rod carrying said arm, means for lowering said rod, and a stationary cam for releasing said gripper when in its lowermost position.

50. A leaf support for stemming machines, 70 comprising a gripper for supporting a leaf by its butt, of means for lowering said gripper, and means for releasing said gripper when in its lowermost position.

51. Leaf spreading mechanism for stemming machines, comprising a suction chamber having spaced walls terminating at their outer edges in air exhausting connections, shafts outside of said walls, and coacting belts operated by said shafts and having operating runs between said walls to pass leaves through said chamber to cause outgoing air to spread them out.

52. Leaf spreading mechanism for stemming machines, comprising a suction chamber having spaced walls terminating at their outer edges in air exhausting connections, shafts outside of said walls and beyond the same, and coacting belts operated by said shafts and having operating runs between 80 said walls for passing leaves through said chamber to cause outgoing air to spread them out and for transporting the outspread leaves away from said chamber.

53. Stemming devices for stemming machines, comprising stem holding means, suction web holding means, and means for causing said stem holding means and said suction web holding means to travel in divergent directions to tear apart the stems and webs of 100 leaves toward their butts.

54. Stemming devices for stemming machines, comprising an apertured cylindrical suction box, a perforated sleeve rotating on and coacting with said box to hold the webs 105 of leaves, and stem holding means rotating in the opposite direction to cause the stems and the webs of the leaves to be torn apart toward their butts.

55. Stemming devices for stemming machines, comprising an apertured cylindrical suction box, a perforated sleeve rotating on and coacting with said box to hold the webs of leaves, a belt coacting with said sleeve to aid suction in holding the webs of leaves, and stem holding means rotating in the opposite direction to cause the stems and the webs of the leaves to be torn apart toward their butts.

56. A stem holding device for stemming machines, comprising a rotating cylinder having axial slots in its periphery, and spring-actuated and cam-controlled gang grippers working in said slots.

57. A stem holding device for leaf stemming machines, comprising a rotating cylinder, stem impaling pins carried by said cylinder, and means for pushing stems off of said pins when separated from the webs of leaves.

58. A stem holding device for leaf stem-

- ming machines, comprising a rotating cylinder, stem impaling pins carried by said cylinder, and eccentrically rotating means for pushing stems off of said pins when separated from the webs of leaves.
- 5 69. A stem holding device for leaf stemming machines, comprising a rotating cylinder, stem impaling pins carried by said cylinder, and a series of fingers working between pins and eccentrically rotating with respect to said cylinder for pushing stems off of said pins when separated from the webs of leaves.
- 10 70. The combination with means for transporting an outspread leaf, of stemming devices receiving the leaf from said means, including stem holding means and web holding means traveling in divergent directions to tear its stem and web apart towards its butt,
- 15 75. Stemming devices for stemming machines comprising stem holding means, web holding means and means for causing said stem holding means to tear the stem from the web, said web holding means including a rotating cylindrical element and a belt having a loop coacting with said element to grip the web beyond the tearing position, and means for adjusting the position of said loop relative to said tearing point.
- 20 80. In testimony whereof we have signed our names to this specification.
- 25 85. RUPERT E. RUNDELL.
- 30 90. GUSTAF E. HAGQUIST.
- 35 95. 61. In a stemming machine, the combination with stem gripping means, of leaf supporting means operating to support the stems of the leaf in the range of action of said stem holding means, and means for relatively adjusting one toward and away from the other to cause said gripping means to selectively grip stem portions of greater than selected thicknesses, without gripping stem portions of less than the selected thicknesses.
- 40 100. 62. Tobacco leaf cleaning means comprising means for lowering a leaf tip foremost, a chamber through which the leaf is lowered with the stem near the center of the chamber, and means for drawing air in near the center 105 of the chamber and out at either side to clean and spread the leaf as it is lowered through the chamber.
- 45 110. 63. In a stemming machine, the combination with means for transporting a tobacco leaf, of pneumatic means for simultaneously spreading the leaf and cleaning both sides thereof.
- 50 115. 64. Cleaning and spreading means for tobacco leaves comprising means for supporting the leaf along the stem and mechanism for directing streams of air from the stem portion across the web of the leaf toward each edge thereof.
- 55 120. 65. In a device for preparing tobacco leaves for use, the combination with devices for supporting a tobacco leaf, of means for producing a stream of air acting transversely of the leaf across the web, said means including mechanism for confining the air close 125 to the surface of the web.
- 60 130. 66. The combination with means for lowering a pendent tobacco leaf, of devices for stemming said leaf including a gang of laterally spaced grippers for gripping the stem despite lateral variations in the position at
